UNITED STATES PATENT OFFICE.

HARRY BATES, OF NEW YORK, N. Y.

MEMORY-CLOCK.

1,385,656.

Specification of Letters Patent. Patented July 26, 1921.

Application filed March 2, 1918. Serial No. 220,098.

To all whom it may concern:

Be it known that I, HARRY BATES, a citizen of the United States, residing at New York, in the county of New York and State 5 of New York, have invented certain new and useful Improvements in Memory-Clocks, of which the following is a specification.

This invention relates more particularly 10 to time-controlled, electrically-operated annunciators having a series of electric circuits closed, at regular intervals, in the movement of a clock, these circuits having, also, a set of auxiliary switches, whereby, when the 15 circuit is closed in the movement of the clock, the alarm will be operated, if the corresponding auxiliary switch has been previously closed.

The object of the invention is, generally, 20 to simplify and otherwise improve the construction of such an apparatus; to provide improved auxiliary switches, which are operated from the front of the casing containing the operative parts of the apparatus; and to provide, in connection with such an apparatus, an improved form of 25 card-memoranda system, so that the user of my memograph or reminder clock may associate a signal, as given, with the appropriate card from which the data or memoranda relating to the appointment, or the like, is obtained.

The invention is graphically illustrated 30 in the accompanying drawings, in which like reference-characters denote corresponding parts throughout the several views. The different figures or views of the drawings 35 may be briefly described as follows:

Figure 1 is a perspective view of my reminder clock;

Fig. 2 is a fragmentary detail view of the memoranda-tray;

Fig. 3 is a view in rear elevation of the reminder clock, the rear plate of the casing 45 being removed to show the interior mechanism;

Fig. 4 is a central, vertical, transverse view;

Fig. 5 is a fragmentary sectional view on 50 the line 5—5, Fig. 4, looking in the direction of the arrows; and

Fig. 6 is a diagrammatic view of the electric circuit.

Referring, now, in detail, to the drawings:

1 designates a casing, of any desired ornamental design, adapted to inclose a clock 2 (of ordinary construction), and provided, in its front wall, with a circular aperture 3, through which the clock dial 4 is visible, 60 and with a second aperture 5 for the reception of an electric lamp or bulb 6.

At the bottom, the casing 1 is expanded, at the sides and front, into a base 7. At the front of the base and disposed above the bottom thereof and parallel therewith is a panel, constituting a support for a preferably removable memoranda-tray, which may be variously constructed, but which, in this instance, comprises a bottom 9, a rear wall 10 70 bearing flatly against the front wall of the casing 1, end walls 11, 11 bearing flatly against the end walls of the base 7, and a series of spaced, vertical plates 12, dividing the tray into a plurality of memoranda- 75 compartments, in this instance twenty-four in number, one compartment for each half hour throughout a period of twelve hours. The compartments are suitably indexed, and, in this instance, such identification may 80 be arranged on the front edge of the bottom 9 of the tray, as shown in Figs. 1 and 2, "12, 12.30, 1, 1.30," etc.

For the sake of cheapness, the casing 1, the tray, and the tray-supporting panel 8 85 are preferably of wood. The casing 1 is provided with a removable rear wall 13, which, of course, is suitably apertured, as at 13', for the insertion of a winding-key to wind the clock 2.

Disposed beneath the memoranda-tray is a series of auxiliary switches 14, one thereof being provided beneath each of the compartments of the tray. Advantageously, the forward ends, only, of these switches project 90 beyond the casing, which arrangement results in a more slight appearance, and these forward ends are provided with porcelain caps 21, constituting insulated handles. Each of these auxiliary switches is of the 100 knife-switch type, and is pivoted, intermediate its length, as at 15, on a metallic bracket 16, which is an ear bent up from a base 17 screwed, as at 18, 18, to an insulating strip 9' extending longitudinally of the base 9 of 105 the casing 1. The several supporting brackets 16 for the auxiliary switches are electrically connected, and a conductor 20 connects one of said brackets 16 with one pole of a battery 19 (as shown in Figs. 4 and 6), one 110

of the screws 18 constituting a binding-post for the terminal of the electrical conductor 20.

In the path of movement of the toe 5 of each knife-switch 14 is a pair of spring contacts 22 carried by a metallic piece 23 screwed to the panel 8. When the knife-switch 14 is moved by forcing downward the handle 21, the toe of the switch moves upward into contact with the spring-contacts 22 and is forced between them and is frictionally retained thereby.

Supported in rear of the clock 2 and spaced therefrom is a disk 28, of insulating material. Conveniently, posts 30 extending rearward from the front supporting plate 32 of the clock 2 have reduced, threaded, rear ends, which project through the disk 28, and carry nuts 31, which clamp the disk 20 on the posts; whereby the disk is supported concentrically with relation to the clock-dial 4.

The disk 28 carries a plurality of fixed contacts 27, disposed in a circular series, the circle being concentric with the clock-dial 4. These contacts are, with relation to the clock-dial, spaced thirty minutes apart, and are in number equal to the auxiliary switches 14. These contacts 27 are individually connected, by electrical conductors 24, to the related contacts 22 of the secondary circuit-controllers 14.

Fixedly carried by the rotating arbor 37 of the hour-hand of the clock is an arm 36, of insulating material. Secured, as at 35, to said arm is a metallic strip 34, of spring material, extending longitudinally of the arm, and provided, at its free end, with a bent terminal 33, constituting a brush to 40 wipe the fixed contacts 27 in the rotation of the hour-hand. This circuit-closer 34, also, is provided with a bent finger 38, constituting a brush wiping against a metallic ring 39 carried by the disk 28 and concentric 45 therewith. The metallic ring 39 is connected, by an electric conductor 41, with the pivot 42 of a switch 49 disposed exteriorly of the casing 1.

The switch 49 is movable between, and is 50 adapted to contact with either one of, two contacts 47, 48, constituting the terminals, respectively, of branches 44 and 45 of the conductor 43 leading to one of the poles of the battery 19. The branch 44 includes a 55 buzzer 46, or other form of audible alarm, and the branch 45 includes the light or lamp 6. Thus, either the lamp or the buzzer may be switched into circuit, and the other cut out.

60 In operation, suppose the user of the reminder-clock desires to be reminded of en-

gagements, etc., at, say, 3 o'clock and 5.30 o'clock. He places a card A, bearing the memorandum concerning the 3 o'clock engagement in the compartment of the memoranda-tray marked "3", and another card bearing data concerning the 5.30 o'clock engagement in the compartment of the memoranda-tray marked "5.30", and pushes downward on the handles 21 of the auxiliary 65 switches 14 corresponding or related to (i. e., disposed beneath) the three o'clock and five-thirty o'clock compartments of the memoranda-tray. Consequently, the circuits will be closed when the circuit controller 24 contacts with the contacts 27 related to the switches 14 which have been previously closed, as stated, and the alarm is sounded, or the lamp 6 lit (according to whether the switch 49 has been thrown to 70 cut in the alarm 46 or the lamp 6), when the hands of the clock 2 indicate three and five o'clock, respectively.

It will be seen that the different parts form a unitary, self-contained, portable 85 memorandum-clock, that may be manufactured at a reasonable cost and sold as an article of manufacture.

Having thus fully described my invention, what I claim as new and desire to secure by 90 Letters-Patent is:

1. In an annunciator clock, a clock mechanism provided with a central hand driving shaft, an arm of insulating material mounted upon said shaft, an annular conductor 95 surrounding said shaft and insulated therefrom, a plurality of binding posts parallel with said shaft and spaced concentric with said shaft at the end of said arm and provided with pointed ends toward said arm 100 and means for longitudinally adjusting said posts, a spring bridge wiping said annular conductor and affixed to said arm at substantially a third the radial distance to said posts, the bridge having a radial spring extending from said affixing point, the extension brushing said points on said posts. 105

2. In an annunciator clock, a plurality of balanced longitudinally extending co-axial bridge levers, insulated handles upon one 110 end of said levers, a housing covering said levers with the handles protruding beyond the housing, relatively insulated contact points mounted above said levers at the end opposed to said handle, a clock mechanism 115 provided with a rotating bridge, and means whereby a circuit is formed by said rotating bridge when at a position determined by downward pressure upon one of said levers.

In testimony whereof, I affix my signature. 120

HARRY BATES.
